Application February 11, 1935, Serial No. 6,048

18 Claims. (Cl. 112—2)

The present invention relates to machines for packing tea and similar materials in individual bags and more particularly is directed to an improved means for finishing tea bags formed 5 with non-tangling type of string handles.

Among the objects of the invention is to generally improve machines of the character described which shall comprise few and simple parts assembled to form novel, efficient and economical additional equipment for operating in combination with existing or newly developed tea bag packaging machines whereby non-tangling string handle tea bags can be produced, and which shall be simple in operation and practical 15 to a high degree in use.

Other objects of this invention will in part be obvious and in part hereinafter pointed out.

The invention accordingly consists in the features of construction, combinations of elements 20 and arrangement of parts which will be exemplified in the construction hereinafter described and of which the scope of application will be indicated in the following claims.

In the accompanying drawings, in which is 25 shown one illustrative embodiment of this invention,

Fig. 1 is a plan view showing an apparatus embodying the invention applied to a tea bag packing machine (only a portion thereof being shown) for finishing the tea bags by providing a non-tangling form of string handles thereon;

Fig. 2 is a sectional view taken on line 2—2 of Fig. 1 showing portions of the machine and equipment assembly in elevation;

Figs. 3 and 4 are sectional views taken on line 35 3—3 of Fig. 1 and line 4—4 in Fig. 3, respectively;

Fig. 5 is a plan view of a portion of the assembly shown in Fig. 1, the various operating parts being shown in position at the end of the 40 sewing operation just before the tea bag is discharged from the equipment;

Figs. 6 and 7 are sectional views, in elevation, taken on line 6—6 of Fig. 5 and line 7—7 in Fig. 6, respectively;

Fig. 8 is a plan of a portion of the loop-forming discharging assembly showing the power transmission and timing elements, and

Fig. 9 is a sectional view taken on line 9—9 of Fig. 8.

Referring in detail to the drawings, the apparatus there shown, embodying the invention applied in combination with tea bag packaging machine, will be described successively as to structure and operation.

55 Structure.—In practicing the invention, a bag

packaging machine may be used of which only parts of units A and B are here shown and described, in combination with the additional equipment H to provide non-tangling string handles for the bag packages. The portions of the bag 5 packaging unit A shown in the drawings is seen to comprise a series of radially extending spaced abutment plates 10 each coacting with a jaw 11 movable relative to one of said plates 10. Each jaw 11 may be made integral with a bar 12 pivotally connected with the ends 13, 13a of a pair of curved arms 14, 14a, respectively. These latter arms 14, 14a are pivotally mounted at 15, 15a, respectively, and tend to move in the direction of the plate 10 by the action of a flat 15 spring 16 anchored at 17 to the body of a turn table 18 which also carries the plates 10, arms 14, 14a and jaws 11. The aforementioned parts 12, 13, 13a, 14 and 14a coact to form a parallelogram pivoting about 15, 15a to permit jaw 11 20 to move toward or away from plate 10. The mechanism operating to move the spaced jaws 11 or that required to charge a tea bag T between plate 10 and jaw 11 forms no part of the present invention and is not shown. 25

A string S terminated by a tag G is fed to unit A by mechanisms similar to those shown and described in the prior patent to Allatt, Reissue No. 16,897, dated March 13th, 1928, so that the string portion thereof is gripped by a pair of 30 fingers 20, 20a in the manner shown in Fig. 1, and is then discharged by a push mechanism mounted on slideable carriage 21 and actuated by a rod 22 so as to deliver both the tea bag T and the tagged string S together into a receiving 35 slot 30 forming part of station C of turret unit B, fingers 20, 20a being opened and jaw 11 retracted by mechanisms not shown. (For a more complete disclosure of this feature, see Fig. 5 of said Allatt's reissued patent referred to above.) 40 The tea bag T and string S, when inserted into slot 30 at C, are crowded into the latter so that the upper end of the tea bag T is gathered to form a closure and is tightly wedged in position in said slot against displacement. 45

Turret unit B may be rotated in proper step by step timed relation to turn table 18 of unit A by means of a drive of the type disclosed in said Allatt reissued patent.

As the turret rotates, the bag T at station C 50 passes in front of guides or guards 31, 31a, acting to maintain the gathered closure in position in slot 30 and arrives at station D. Here a pair of shears 32 actuated in properly timed relation and provided at one extremity with a cross bar 33 55

acting as a guide to the lower member of the shear, moves so as to trim off those portions of the top of the bag T and the string extending above a predetermined level. Turret B then rotates so as to bring the bag to station E where a suitable seal or fastener is applied to the gathered closure, as for example a metal band M (aluminum) which may be forced by a plunger 34 around both the neck of the tea bag T and string S so as to bind them together in the manner shown in Fig. 3.

Plunger 34 is carried by a cross head 35 reciprocating under the action of an arm 36 connected therewith, cross head 35 being retained in its movements by a pair of fixed guides 39, 39a. The aluminum bands M are fed up in front of plunger 34 by a turn table 48 more fully described in said reissued patent to Allatt already referred to, wherein a detailed description will also be found of the manner in which said aluminum band is bent so as to enclose the top or neck of the tea bag T and its string S.

Turret B then rotates into station F where a series of operations are effected for providing a non-tangling tagged string handle for the tea bag in the form of a drawn loop of the string passing through the tea bag. These operations together with the equipment for effecting the same embody the objects of the present invention.

30 The operations at station F comprise (1) driving a needle P through the tea bag T, (2) threading a portion of the string into a notch or open eye N formed at the leading end adjacent the point of the needle P after said needle has traversed the body of the tea bag, (3) drawing the needle P back through the tea bag together with that portion of the string S in the form of a loop which is threaded into the notch N thereof, (4) unthreading the string from the needle so as to leave string loop free, and (5) ejecting the tea bag from the slot 30 in which it is sustained at station F. All of the mechanisms for effecting these operations are included in equipment H.

The mechanism for driving the needle P through the tea bag T and for retracting the same comprise (Figs. 1, 2, 5, and 9) a needle holder or post 58 provided with a set screw 54 for securing the needle P in position, said post forming part of a sliding carriage or frame 52, a lever 53 pivotally connected to carriage 52 at 54 and fulcrumed at 55, an adjustable link 56 pivotally connected to lever 53 at 57, a lever 58 pinned to rock shaft 59 and having one end connected in driving relation to link 56 at 60.

55 Another lever 58a also pinned to turn with shaft 59 is connected to link 61 pivoted to one end 62 of a link 63, the latter carrying a cam roller 64, the other end 62a of said link 63 being pivoted on a shaft 66. A cam 65 rotating with a drive shaft 67 engages the roller 64 and is operative to actuate all of the foregoing interconnected links and levers for actuating the needle movement.

The mechanism parts cooperating to thread 65 or guide a mid-portion of the string S into the notch N of the needle P include a plate 70 rigidly mounted on carriage 52, a pair of screw-studs or stops 71, 71a rigidly mounted on plate 70, a second plate 72 slidably supported on plate 70 and having a slot 73 formed therethrough guidably engaging with stops 71, 71a, and a cam-shaped portion or ramp 72a formed thereon as shown, a spring 74 anchored at 75 to plate 70 and at 76 to plate 72, a pair of threading fingers 75 or spaced arms 80 mounted to move together and

pivotedly supported at 81, a spring 82 tending to draw arms 80 from the string S, and a roller 83 carried on one of said arms 80 and positioned to ride onto ramp 72a formed on one end of plate 72, the foregoing elements being designed and positioned so that when carriage 52 moves from the position shown in Fig. 1, roller 83 engages on plate ramp 72a so as to swing arms 80 past the path of the needle and force the string S into the needle notch N.

10 The parts of the apparatus acting to retract the needle P are the same as the ones already described for driving the needle P through the body of the tea bag T.

When the needle P arrives at the end of its 15 retracting course, it is caused to rapidly reverse direction and begins to move back towards station F, as indicated in dotted line position of the holder 58 in Fig. 6. The string engaged in the notch N of the needle is stretched and under tension 20 before the retracting movement of the needle P and, when reversal occurs, is quickly released from this tension strain and springs out of the needle notch N.

Cam 65 is formed and designed so that the 25 speed of the needle at reversal is such as to release the tension on the string rapidly enough to effect release.

In order to support the tea bag T and to guide 30 the needle P during its course in opposite directions through the body of the tea bag, an oscillatably supporting frame 90 is provided having a bracket 91 mounted on one end thereof, said bracket carrying a spring plate 92 (Figs. 3 and 4) formed with a tube, nozzle or teat 93 positioned so that its axis is colinear with the path of movement of the needle P. Spring plate 92 acts to press the body of the bag against a fixed pressor plate 95 positioned on the other side of the tea bag T and to support the tea bag resiliently 40 when the needle P is being retracted. Frame 90 is oscillated by a link 96 actuated by an arm 97 pivoted on shaft 66 provided with a roller 98 riding on a cam 99. A spring 98a retains the roller 98 against cam 99.

45 The string having been drawn through the tea bag T to form a non-tangling loop, there remains only the operation of discharging the tea bag T from station F. This is effected by two independent groups of mechanisms, one acting to withdraw the finished tea bag from station F including following up to insure ejection of the tea bag from this station and a finger gripping means for supporting and moving the bag T after the same is dislodged from the station F.

The discharge of the bag T from the station F is primarily accomplished by a spaced pusher fork 130 which straddles the plate having the slot at station F as is shown in Figs. 1 and 3, said fork being mounted to terminate an arm 131 carried on frame 90. Said fork grasps the neck of the tea bag T and on the receding movement of the frame 90 from the station F, it dislodges the tea bag T therefrom.

The tea bag finger gripping means for supporting and moving the bag T is oscillatably supported on the frame of the machine and includes a pair of fingers 100, 100a mounted to oscillate together and to and from each other, each of said fingers being pivotally mounted at 101, 101a and being provided with gear teeth 102 in mesh with one another, each finger also carrying an adjustable stop 103, a plate 104 supporting pivots 101, 101a and being itself pivotally supported at 105, a spring 106 inter-connecting fingers 100, 100a 70

which are anchored to pins 107, 107a, pin 107a being positioned on an arm 108 integral with finger 100a and sliding in an open slot 109 whose extremities act as stops. A rod 110 at its upper end is pivotally connected to one extremity of plate 104 at 111 and is provided with a compression spring 112 tending to force plate 104 into the dotted line position shown in Fig. 9. A free end of lever 113 engages with the lower extremity of rod 110 in a loose coupling connection 114, said lever carries a cam roller 115 which rides on a cam 116, and a tension spring 117 is provided to maintain roller 115 in contact with cam 116 as shown in Fig. 9.

From the foregoing description it will be seen that, when lever 110 is moved by cam 116 from the full-line position in Fig. 9 to that indicated in the dot and dash line, rod 110 will move upward so as to tilt plate 104 about 105 as an axis. When this happens, arm 108 will move in its guiding slot 109 from the position shown in Fig. 1 to the position shown in Fig. 5 where it will abut against one end of the slot 109. Any further tilting movement of plate 104 will then cause spring 106 to move into the position shown in Fig. 5 across the axis of pivots 101, 101a. Gear teeth 102 will then act to swing fingers 100, 100a toward one another so as to grip the tea bag T. When plate 104 swings from its full line position toward the dot and dash line position shown in Fig. 9, the tea bag T which is at first gripped by fingers 100, 100a, is released and discharged into a conveyor 120 (see Fig. 2) by a series of operations exactly inverse to those above described.

In the event that fork 130 should fail to remove the tea-bag from the slot at station F, an auxiliary pick operating in a similar manner to the ejector described in the said Allatt re-issue patent already referred to, comes into action to insure ejection of the bag.

This auxiliary ejecting pick comprises a cam controlled lever arm 200 having a forked extremity 201, an oscillatable arm 202 fitting into forked extremity 201, and a rod 203 fixed by a binding post 204 to arm 202 and terminating in a pointed bent portion 205 (Fig. 3). The foregoing elements are designed and positioned so that, when frame 90 moves from the position shown in Fig. 1 towards the position shown in Fig. 5, fork 130 first acts to engage the tea-bag and then, as frame 90 swings so as to tilt rod 202 and bring point 205 into contact with the top of the tea-bag in the manner shown in Fig. 3. Further outward movement of frame 90 will then cause point or picker 205 to eject the tea-bag T from the slot in station F in case the bag T should stick.

The driving and timing mechanism connected to units A, B and equipment H are such as to make all the operations continuous and automatic.

Operation.—The mechanisms hereinabove described operate in the following manner: Filled tea-bags T are fed to turn table 18 of unit A by a suitable mechanism (not shown) and gripped between plates 10 and jaws 11, the latter being actuated to open and close at the proper time by a cam or other convenient form of control mechanism (not shown). When turn table 18 rotates so as to bring a tea-bag T into line with station C of unit B, fingers 20, 20a have already seized a string S which terminates in a tag G, said string S being delivered to said fingers 20, 20a by a mechanism (not shown). This latter may

be like that described in said Allatt reissued patent. Slide 21 actuated by rod 22 then comes into action to push the tea bag T and string S into slot 30 at station C, fingers 20, 20a and jaw 11 being retracted simultaneously by appropriate mechanisms to release the tea bag T and string S. As unit B rotates towards station D, by a step by step movement, guards or guides 31, 31a act to maintain the tea bag T firmly in slot 30. As soon as the tea bag T arrives at station D, shears 32 are moved from open to a closed position so as to trim off the top of the tea bag T together with its accompanying string. Unit B then rotates one step towards station E where plunger 34 is actuated by rod 36 to apply an aluminum band around the neck of the tea bag. Unit B then again rotates a step so as to occupy station F. Here, after frame 90 has swung into the position shown in Figure 1 so that the tea bag T is gripped between presser plate 95 and spring plate or guide 92, lever 53 swings carriage 52 supporting the needle into the position shown in Fig. 1. As carriage 52 moves into the position shown in this figure, roller 83 rides over ramp 72a so as to swing arms 80 from the position shown in Fig. 5 into the position represented in Fig. 1. A mid-portion of the string S is thus forced into the needle notch N.

It will be noted that, since plate 72 is mounted to slide on plate 70, there will be a tendency for such sliding action to occur when roller 83 contacts with ramp 72a. Spring 74, however, will tend to prevent excessive sliding movement from occurring. Once roll 83 has ridden over ramp 72a, spring 74 will act to bring plates 70 and 72 into the position shown in Fig. 1.

As soon as the needle begins its retracting movement towards the position illustrated in Fig. 5, these portions of the string engaged on the end of arms 80 will be drawn off of the latter end, as the retracting movement continues, arms 80, under the guiding action of roller 83 will ride back over ramp 72a into the position shown in Fig. 5. It will be obvious from inspection of the drawings that this retracting movement is effected by lever 53 acting on carriage 52.

Once the needle P reaches its fully retracted position, cam 65 acts to quickly move the needle back towards the dotted line position represented in Fig. 6. The loop of string engaged in the notch of the needle P, hitherto under tension as shown in full line in Fig. 6 will spring out into the dot and dash line position shown in the same figure and disengaged from the notch in the needle the cam 65 being properly designed to effect reversal at the proper speed. As soon as the needle is unthreaded, cam 116 comes into action to move lever 113 so as to tilt plate 104 and bring fingers 100, 100a into gripping relation with respect to the tea bag T. Frame 90 carrying the fork 130 together with carriage 52 and the mechanisms actuating fingers 100, 100a then begin to swing outward, as shown in Fig. 5, so as to eject the tea bag from station F. As frame 90 approaches the end of its outward course, plate 104 tilts downward so that arm 108 engages with one end of slot 109 thus causing spring 106 to move across pivots 101. Gear teeth 102 will then act to swing fingers 100, 100a into the open position illustrated in Fig. 1 and the tea bag will drop into an appropriately positioned conveyor 120, shown in Fig. 2.

Should the fork 130 and the fingers 100, 100a fail to detach the tea bag from station F, picker 205, actuated by the parts 200, 201, 202, and 203,

will act to assist in forcibly ejecting the bag T in the manner already described.

It is to be noted that the nozzle 93 preferably is made with a passage of sufficient size only to 5 permit the free movement of the needle P and the string S threaded therein. Said nozzle serves to retain the strands of the looped string passing therethrough together so that when the needle P moves to unthread the string, the bight 10 of the looped portion of the string engaging the notch N alone is spread out, as shown in Fig. 6, to facilitate the disengagement of the string from the nozzle.

Units A, B and the equipment H will then be 15 ready for a new series of operation for forming non-tangling string handle bags.

It will thus be seen that there is provided apparatus and a method in which the several objects of this invention are achieved and which 20 are well adapted to meet the conditions of practical use.

As various possible embodiments might be made of the above invention, and as various changes 25 might be made in the embodiment above set forth, it is to be understood that all matter herein set forth or shown in the accompanying drawings is to be interpreted as illustrative and not in a limiting sense.

Having thus described our invention, we claim 30 as new and desire to secure by Letters Patent:

1. In a machine of the character described, a needle having an open notch adapted to engage a string, needle supporting means, means for holding a tea bag in position, means for successively moving said needle supporting means toward and away from said tea bag supporting means, said needle support moving means being constructed and arranged to effect reversal of the needle at a speed sufficient to disengage the 40 string from the needle notch.

2. In combination with a machine provided with means for holding a bag package in position and a needle having an open notch formed adjacent the point thereof adapted to engage a string, 45 of means for guiding the string into the notch of the needle including an element operative to intermittently contact with said string at two spaced points.

3. In combination, a machine provided with 50 bag package supporting means, a needle, and needle actuating means operative to drive said needle successively in opposite directions through said bag, and means operative to engage with a bag package for ejecting the same from said supporting means.

4. A loop stitching machine for a bag package comprising a needle having an open eye adapted to receive a string, means for driving the needle through the package and withdrawing same, and 60 means for engaging a string in the needle eye when the needle is inserted through said package, said driving means being so constructed and arranged to disengage the string on withdrawal of the needle from said package.

5. In combination with a machine provided 65 with bag package supporting means, a needle and needle actuating means operative to drive said needle successively in opposite directions through a tea bag, of ejecting means operative to discharge said bag package from said supporting means, and means for gripping the discharged tea bag.

6. In a method of forming a non-tangling string handle bag package, the step of releasing 70 a looped string threaded in an open notch of the

needle extending through the package by quickly moving the needle while retaining mid-portions of the loop strands together to cause the bight of the loop engaging the notch to spread and free itself therefrom.

7. In combination with a machine provided with means for successively driving a needle in opposite directions through a bag package, of supporting means positioned to maintain a bag package in the path of movement of said needle 10 including a resilient abutment portion.

8. In combination with a machine provided with means for successively driving a needle in opposite directions through a bag package, of supporting means positioned to maintain a bag 15 package in the path of movement of said needle, said supporting means including a nozzle portion wherethrough the needle passes.

9. In combination with a machine provided with a needle and means for successively driving 20 said needle in opposite directions through a bag package, of supporting means positioned to maintain a bag package in the path of movement of said needle, said supporting means including a 25 pair of gripping portions, the gripping portions situated on that side of the bag package which the needle first penetrates being resiliently mounted.

10. In combination with a machine provided 30 with a needle and means for successively driving said needle in opposite directions through a bag package, of supporting means positioned to maintain a bag package in the path of movement of said needle, said supporting means including 35 a pair of gripping portions, the gripping portions situated on that side of the bag package which the needle first penetrates being resiliently mounted and provided with tubular guiding means positioned co-axially with the path of movement of the needle.

11. In combination with a machine provided 40 with bag package supporting means, a needle, and means for supporting and successively driving said needle in opposite directions through a bag package, ejecting means comprising a pair of gripping fingers formed and positioned to take hold of the body of the bag package, and means for moving said fingers toward and away from one another.

12. The combination defined in claim 11 including means operative to move said gripping fingers away from said supporting means.

13. The combination defined in claim 11 including means operative to swing said gripping fingers toward and away from said supporting means.

14. In combination with a machine provided with bag package supporting means, means for ejecting the package from the supporting means, 60 a pair of pivotally mounted fingers positioned to move toward and away from one another to grip and to release a bag package, finger supporting means, and means for oscillating said finger supporting means.

15. In combination with a machine provided with bag package supporting means, a needle, and means for supporting and driving said needle through a bag package held in said supporting means, needle threading means comprising a pair 70 of oscillatable arms positioned to straddle the leading end of said needle when said needle has traversed through the bag package, and means operative to oscillate said arms toward and away from the course of said needle.

16. In combination with a machine provided with bag package supporting means, a needle, and means for driving said needle through a bag package held in said supporting means, of needle threading means comprising a pair of oscillatable arms positioned to move across opposite sides of the path of traverse of the needle.

17. In combination with a string handle bag packaging machine having means to discharge a finished package, an apparatus driven by said machine in timed relation with the operation of said machine to provide a non-tangling loop in the string handle drawn through the bag, said ap-

paratus being connected with the machine parts to operate prior to said discharge means.

18. An automatic machine of the character described including means for attaching a string handle to a bag package, means for drawing a looped portion of the string handle through the bag, and means to discharge a finished bag package, said string handle attachment means, looped portion drawing means and discharge means being cooperatively assembled to operate successively in timed relation. 5 10
